UNITED STATES PATENT OFFICE.

WILLIAM WALTER OWEN, OF ELGIN, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

1,356,654.

Specification of Letters Patent.

Patented Oct. 26, 1920.

Application filed May 7, 1917. Serial No. 167,155.

To all whom it may concern:

Be it known that I, WILLIAM WALTER OWEN, a citizen of the United States of America, and a resident of Elgin, county 5 of Kane, and State of Illinois, have invented certain new and useful Improvements in Measured-Service Telephone Systems, of which the following is a specification.

My invention relates in general to measured service telephone systems and has particular reference to improved measured service equipment for use in operating a subscriber's meter. More specifically my invention relates to an improved method of 10 assessing toll for long distance connections, by operating the subscriber's meter automatically, whereby the subscriber may be charged according to the number of exchanges through which his call may extend 15 and also in accordance with the length of the trunk line between said exchanges and whereby all long distance calls may be set up and accurately charged for without the necessity of an operator's supervision. 20

25 In the drawings I have illustrated one embodiment of my invention in connection with automatic switches of well known type and construction but I do not wish to be restricted to any particular type, my invention being equally adapted to any known type of system.

Figures 1, 2, 3 and 4 show an established connection from a subscriber to one exchange (Figs. 1 and 2), through a selector and a selector repeater of an intervening exchange (Fig. 3), and through a selector and a connector of a third exchange, to a subscriber in the third exchange (Fig. 4).

Although the elimination of the operator 40 in establishing local calls in one exchange has been made possible by the use of automatic switches and equipment, it has heretofore been impossible to give purely automatic service to subscribers when long distance connections are desired. That is, although the automatic switches can easily take care of such service, there has been no means of charging the proper rate to the calling subscriber for such service without

the intervention of a supervising operator, 50 whose business was to note the distance over which the subscriber desired to call and then, upon the response of the called subscriber, to charge or assess the proper rate for such distance upon the calling subscriber's meter. This method of operation has caused a material slowing up in the speed of such long distance calls. 55

My invention does away entirely with the need for a supervising operator either in 60 local or long distance calls and is particularly valuable in a community in which a number of small towns or cities are near together and are closely associated, and where parties in each of these different cities desire to call frequently to any other city 65 without having to first call an operator.

In order to accomplish this result I have provided a register controlling mechanism for each outgoing switch in an exchange, in 70 this case a selector repeater, which mechanism is operated one step for each digit which is sent out beyond the first (or calling) exchange, and which is released upon the response of the called subscriber and 75 allowed to transmit a number of impulses of booster battery to the calling subscriber's meter. The number of impulses sent to the meter being the same or in the proper proportion, to the number of digits sent out by 80 the calling subscriber.

The ratio between the digits sent out and the impulses delivered to the meter is determined by the number of digits necessary to call through an exchange and the length 85 of trunk line between exchanges. In this embodiment of my invention I have assumed that the trunk lines shown are of equal length, or so nearly equal as to require the same unit of charge, and that each exchange requires three digits, or three operations of the calling device, either to call through an exchange or to call a subscriber in an exchange. It will readily be seen that the trunking can be arranged to meet any 90 further requirement and that, in case more, or less, digits are required to call through an exchange, the number of projections on

the cam wheels of the impulse sender may be varied accordingly.

My invention may be more clearly understood by reference to the drawings.

- 5 The substation A, (Fig. 1) may be of any well known common battery type and comprises the transmitter 2, receiver 3, calling device 4, controlling the impulse springs 5 and 6, and switch hook 7, for controlling 10 the usual switch hook springs to disconnect the ringer 8 and condenser 9 and to connect the transmitter and receiver, in series with the impulse springs, across the line conductors 10 and 11 leading to the exchange.
- 15 The line switch C in which the line conductors 10 and 11 terminate is similar in all respects to that shown in U. S. Letters Patent #1,186,823, granted June 18, 1916, to Frank Newforth, Jr., and comprises 20 among other details a plunger (not shown) attached to the end of a so-called plunger arm 12, which is controlled by the magnet 18, to force into contact, in pairs, a bank of contact springs 14 to 21 inclusive, to 25 thereby extend the line conductors 10 and 11 to a selector switch D.

The master switch G (Fig. 1) is also similar in all respects to that shown in the above mentioned patent and need not be further 30 described here.

The selector switch D (Fig. 1) is similar in construction to that shown in U. S. Letters Patent #815,321, granted March 13, 1906 to Keith Erickson and Erickson except 35 that the side switch has been omitted and the circuits have been somewhat modified to adapt it to the modern two-wire system of operation. It comprises among other details a line relay 22, bridge cut-off relay 23, vertical magnet 24, rotary magnet 25, release magnet 27, rotary interrupter relay 26 and a pair of relays 28 and 29, which are slow-acting, that is, slow to deenergize when their energizing circuits are broken, and which 40 control the switching over from one magnet to the other. The vertical magnet 24 and rotary magnet 25, are controlled by the line relay 22 to raise the shaft wipers 30, 31 and 32 to rotate them into engagement with 45 some pair of contacts similar to 33, 34 and 35.

The selector repeater E, (Fig. 2) is similar in construction to that shown in Patent No. 1,312,558, T. G. Martin, Aug. 12, 1919, with 55 the addition of the register controlling mechanism R adapted to operate in accordance with my invention, and certain new and useful circuit connections in connection therewith. This selector repeater is provided with 5 wipers, 36 to 40 inclusive, the wipers 36 and 40 being line wipers adapted to be connected to contacts in the line bank which lead through trunk lines to other exchanges. The wipers 37 and 38 are private 60 wipers for testing purposes. The banks

over which these wipers are adapted to rotate have no connection leading to the other exchanges but are connected locally in order to divide the trunk lines leading from the corresponding line contacts into groups and sub-groups, as pointed out in said prior application. The wiper 39 is used only for discriminating purposes and is connected to the booster battery B¹². The contacts in the bank over which the wiper 39 rotates are 70 connected to the springs of the different cam wheels of the register mechanism R. In case certain trunk lines leading from this bank extend to a city or exchange which is a greater distance from the originating exchange than usual, and which requires double the rate of charge per digit, then this booster battery is connected to a cam wheel of the register mechanism which has double the number of teeth or projections, so that 75 the number of the impulses returned to the meter will be double the number of digits transmitted. This selector repeater comprises among other details the line relay 45, back bridge relay 46, private magnet 47, 80 busy test relay 48, and a number of auxiliary relays, several of which, namely relays 54, 53, 51, 50 and 49, are slow to deenergize when their energizing circuits are broken. The movement of the shaft wipers 85 is controlled through the medium of these relays and their contacts and by means of the vertical magnet 58 and rotary magnet 57, the control of the line relay over said magnets being switched from one to the 90 other by means of the usual side switch comprising the wipers 71, 72, 73 and 74 controlled by the usual private magnet 47.

Each selector repeater is provided with a register controlling mechanism R comprising a shaft 65, a pair of cam wheels 63 and 64, a ratchet wheel 61 associated with the cam wheel 63, a ratchet 62 associated with the cam wheel 64, a stepping magnet 60 for driving said shaft in a counter clockwise 100 direction, and a release magnet 59, which upon energizing withdraws its armature (which acts as a catch) from the teeth of the ratchet 62, and allows the clock spring to return the shaft and cam wheels to normal position. The cam wheels are loose on the shaft 65 and remain in normal position while the stepping magnet drives the shaft in a counter clockwise direction. However when the shaft is returned by the clock 110 spring, the cam wheels are rotated in a clockwise direction with the shaft by means of the catches or dogs 70 and 70^a, thereby bringing the springs 66 and 67 and 68 and 69 into engagement a number of times according to the number of teeth on the cam wheels. These teeth may be varied in number according to requirement as hereinbefore pointed out. The stepping magnet 60 of the mechanism is controlled by the slow-acting 115 120 125 130

relay 53, which relay is operated only once for each set of impulses transmitted over the trunk line leading to the next exchange. The slow-acting relay 54 is used for discriminating purposes and is energized only when an incoming selector seizes the line to the selector repeater as will be pointed out. An additional relay 51 is also provided to release the register controlling mechanism R and prevent it from delivering impulses to a subscriber's meter in case a call is set up and the called subscriber fails to respond.

The selector D' (Fig. 3) is similar to the selector D (Fig. 1) with the exception of the magnet 75 which is legged off from the release trunk to battery. This selector is accessible only to incoming calls from selector repeaters in another exchange. The magnet 75 is for the purpose of energizing the relays, similar to 54, in the selector repeater with which this incoming selector connects, when the call originates in another exchange.

The selector repeater E' (Fig. 3) is similar in all respects to the selector repeater E (Fig. 2).

The selector D² (Fig. 4) is an incoming selector of the third exchange similar to the selector D' (Fig. 3).

The connector switch F (Fig. 4) is similar in all respects to the connector shown in the before mentioned Letters Patent #1,186,823 and is of the booster battery type, that is, when the called man answers, an impulse of current from the booster battery B⁴⁴ is transmitted back over the release trunk to the calling subscriber's meter. This impulse of booster current is effective only in case a call is local to one exchange. The back bridge of this connector switch also reverses the battery in the trunk line leading back toward the calling line and this reversal is effective when a call is received from another exchange, to release the register controlling mechanism of the selector repeater in the originating exchange. The connector F comprises among other details the line relay 134, which is bridged across the line conductors through the springs of the back bridge relay 133, the release relay 135, busy relay 136, series relay 137, ring cut-off relay 138, ringing relay 139, wiper cut-off relay 140, additional back bridge relay 132, and auxiliary relay 276. These relays control the vertical magnet 142, and rotary magnet 141, to step the wipers 146, 147 and 148, into engagement with a desired line.

The substation A' and line switch C' are in all respects similar to the substation A and the line switch C.

Having given a general description of the apparatus involved I will now explain in detail how a subscriber at substation A may obtain connection with the subscriber at

substation A' and how the proper charge may be assessed upon the meter of the calling subscriber. We will assume for the purpose of this explanation that three digits are required to call through each exchange 70 shown, one for each selector and two for each selector-repeater and connector. The subscriber at A must therefore send three digits to call out of his own exchange, three to call through the intervening exchange, 71 and three to call a subscriber in the third exchange. It will be understood that this arrangement is only arbitrary and may be varied at will to suit existing conditions.

Upon the removal of the receiver at the 80 substation A from the switch-hook, the talking circuit of the substation is bridged across the line conductors 10 and 11 by the hook switch springs, thereby closing the circuit of the line relay 149 of the line switch C. 85 This circuit extends from ground G⁴ through springs 150 and 151, line 11, substation A, line 10, springs 152 and 153, and line relay 149 to battery B. Relay 149, upon energizing, closes the circuit of the operating winding 154, which energizes and disconnects the relay 149 from the line and thrusts the plunger into the terminals of the trunk before which it is held by the master switch. The springs 14 and 18 and 17 and 21 being 95 pressed together, extend the connection to the selector switch D, and close an energizing circuit for the line relay 22 thereof, which circuit extends from ground G³ through the lower winding of relay 22, 100 springs 166 and 165, springs 21 and 17, to and through the substation A and back through springs 14 and 18, 157 and 156, and upper winding of relay 22 to battery B'. The line relay, upon energizing, closes a circuit from ground G⁴ through springs 168 and 167, to the relay 28 and battery B'. The relay 28, upon energizing, supplies a holding ground for the winding 155 of the line switch C from ground G⁵ to hold the plunger in engagement with the bank springs after the relay 149 has fallen back. Although a branch of the circuit extending to winding 155 also extends through the meter J to battery, the meter is not operatively energized, 110 the winding thereof being of comparatively high resistance and the armature being adjusted so as not to operate by current from the battery B. The meter J is somewhat different than the meter shown in said Letters Patent, in that, it will not hold up after it has been once operated, but will de-energize after each impulse of booster battery. The preliminary non-numerical operations being completed, the line relay 22 is now operated 115 in accordance with the first digit of the called number to operate the vertical magnet 24 to step the wipers 30, 31 and 32 to some level of the banks, from the contacts of which, trunk lines lead to selector-repeaters 120 130

which have access to outgoing trunk lines. As soon as the desired level is reached and the impulses cease, the rotary magnet 25 is operated to rotate the wipers into engagement with an idle one of said trunk lines, which we will assume leads to the selector repeater E (Fig. 2). As soon as this idle trunk line is found the bridge cut-off relay 23, which, during the rotation over busy trunk lines has been short circuited by the ground on the private contacts, energizes over the following circuit: ground G⁵, armature 170 and its front contact, relay 23, interrupter springs 171 of the rotary magnet, off-normal springs 172, and through relay 26 to battery B⁴. The relay 26 is of a lower resistance than relay 23, and does not energize over this circuit. The relay 23 however, energizes, and connects the relays of the switch D from the line conductors and extends the line conductors 10 and 11 through the wipers 30 and 33 and 31 and 35 to the line relay 45 of the selector repeater.

The line relay 45, of selector-repeater E (Fig. 2) energizes over the following circuit: ground G⁶, lower winding of relay 45, springs 178 and 176 of relay 46, contact 35, wiper 31, springs 164 and 165, springs 21 and 17, line conductor 11, substation A, line conductor 10, springs 14 and 18, springs 157 and 158, wiper 30, contact 33, springs 175 and 173, and through the upper winding of relay 45 to battery B⁶. Relay 45 upon energizing over this circuit, closes a circuit from ground G⁷ through springs 180 and 181 and relay 50 to battery B⁷. The relay 50, upon energizing, supplies a holding ground for the relay 23 of selector D over the following circuit: ground G⁸, springs 186 and 187, through the low resistance relay 54, contact 34, wiper 32, springs 160 and 161, relay 23, springs 171, off-normal springs 172, and relay 26 to battery B⁴. The relays 26 and 54 do not energize over this circuit in series with the high resistance relay 23. The relay 23 is however held in its operated position to maintain the connection through to the selector repeater.

The subscriber at the calling substation now operates his calling device for the second digit, thereby momentarily interrupting the circuit of the line relay 45 of the selector repeater E a number of times, depending upon the level of the bank in which the trunk with which he desires to connect is located. The relay 50 is slow acting and retains its armatures in operated position during the energization and deenergization of the line relay. Each time the line relay 45 deenergizes, therefore, a circuit is closed from ground G⁷ through the springs 180 and 179, springs 189 and 190, relay 49, vertical magnet 58, and side switch wiper 71 (in first position) to battery B⁸. The impulses transmitted through the vertical magnet

cause said magnet to raise the wipers to a position opposite the desired level of bank contacts, the first sub-group of which level we will assume is connected to incoming selectors in the third exchange similar to D¹ (Fig. 3). The relay 49, which is included in this circuit in series with the vertical magnet is a slow-acting relay and remains energized during the entire time the vertical magnet is operating. In its energized position the relay 49 completes a circuit from ground G⁹ through springs 191 and 193 and private magnet 47 to battery B¹¹. When the relay 49 deenergizes after the last impulse is delivered to the vertical magnet, it breaks the circuit of the private magnet 47, which thereupon deenergizes and allows the side switch to pass from first to second position. The side switch wiper 71, in passing from first to second position, transfers the battery connection from the vertical magnet 58 to the rotary magnet 57. Therefore when the calling subscriber operates his calling device for the next or third digit the operation of the line relay 45 transmits a series of impulses through the rotary magnet to rotate the wipers 36, 37, 38, 39 and 40 onto the first trunk line of the first group which in this case leads to the selector D¹ (Fig. 3). After the impulses for this digit cease the relay 49 again deenergizes and allows the side to pass from second to third position, that is, assuming this trunk line to be idle. If this trunk line had been busy however the wiper 37 would have found the contact with which it engaged provided with a guarding ground potential. This guarding potential would have provided an energizing circuit for the relay 55, extending from wiper 37, side switch wiper 73 (in second position), and relay 55 to battery B⁹. The relay 55, upon energizing, completes a circuit from ground G¹⁰ through springs 194 and 195 and the private magnet 47 to battery B¹¹. This circuit maintains the private magnet energized after the relay 49 is deenergized and therefore holds the side switch in second position. The deenergization of the relay 49 after this set of impulses closes a new circuit for the rotary magnet from ground G⁹, springs 191 and 192, springs 196 and 197 of relay 55, springs 198 and 199, springs 200 and 201 of relay 48, rotary magnet 57, and side switch wiper 71 to battery B⁸. The rotary magnet will energize over this circuit to step the shaft wipers to the next trunk line, and also closes a circuit from ground G¹¹ through springs 202 and relay 56 to battery B¹¹. The relay 56, upon energizing, interrupts the circuit of the rotary magnet at the springs 198 and 199. The rotary magnet in turn deenergizes and breaks the circuit of the relay 56, which in turn deenergizes and again closes the circuit of the ro-

tary magnet. The relay 55 will remain energized as long as the wiper 37 continues to engage grounded contacts of busy trunk lines, and the rotary magnet will continue 5 to advance the wipers step-by-step until a nongrounded contact is found, which will permit the relay 55 to deenergize, or until the wipers 37 and 38 engage a pair of contacts which are connected together. The 10 last trunk line of each subgroup has a pair of contacts similar to 42 and 43, which are connected together and the selector repeater upon being advanced to this last trunk line will come to rest whether the line associated 15 therewith is idle or busy and if busy the side switch is locked in second position and a busy tone given to the calling subscriber in the manner pointed out in said prior application #655,985.

20 When the wipers of the selector repeater come to rest upon the contacts of an idle trunk line and the side switch passes to third position as has been explained, the connection is completed with the trunk conductors 25 203 and 204 by the closure of the back contacts 205 and 206 of the private magnet. The side switch wiper 73 upon passing to third position extends a guarding potential from ground G^{12} through the wiper 73 and 30 the private wiper 37 to the private bank contact of the seized trunk line in the banks of all switches which have access thereto. The side switch wiper 74, upon reaching third position, completes a bridge across the trunk 35 conductors 203 and 204, whereupon the line relay 77 of the selector D' (Fig. 3) becomes energized over a circuit from ground G^{13} , through the lower winding of relay 77, springs 215 and 214, conductor 204, contact 40 45, wiper 40, side switch wiper 74, impedance coil 216, lower winding of back bridge relay 46, springs 183 and 182 of line relay 45, wiper 36, contact 41, conductor 203, springs 208 and 207, and upper winding of 45 relay 77 to battery B^{16} . The line relay 77 energizes over this circuit and closes the circuit of relay 78. The relay 46 of the selector repeater E one winding of which was included in the above traced circuit, does not 50 energize at this time, the current flowing in the lower winding being in the opposite direction to that flowing in the upper winding. The circuit for the upper winding of said relay may be traced from ground G^{14} 55 through springs 217 (which were closed on the first vertical step of the switch E) and through the upper winding of relay 46 to battery B^{16} . The relay 46 requires the energization of both windings in the same direction in order to operatively energize.

When the substation calling device is operated for the 4th digit the circuit of the line relay 45 of the selector repeater E is again interrupted momentarily a number of times, 60 65 The separation of the springs 183 and 182 at this time, opens the bridge across the trunk conductors 203 and 204, thereby breaking the circuit of the line relay 77 of selector D'. The line relay 77 in response to the opening and closing of this bridge operates 70 in the same manner as the line relay 22 of selector D (Fig. 1) to control the vertical and rotary magnets 82 and 83, to pick out an idle trunk. Each time the line relay 45 of the selector repeater E deenergizes to repeat an impulse to the line relay of the connector, a circuit is closed from ground G^7 through springs 180 and 179, springs 189 and 190, relay 49, relay 53, and side switch wiper 71 to battery B^8 . The operation of 80 the relay 49 is functionless and simply causes the private magnet to open the trunk conductors leading back to the condensers while impulses are being repeated. The relay 53, being slow-acting, remains in its 85 energized position during the entire time the relay 45 is operating in response to a digit. This operation of the relay 53 accomplishes a double result, namely, the short circuiting of the resistance 216 and one 90 winding of relay 46, to remove their resistance from the circuit of the line relay 77 of selector D', and the operation of the stepping magnet 60 of the register controlling mechanism R. The circuit for the magnet 95 60 may be traced from ground G^{15} through springs 218 and 219, springs 220 and 221 and magnet 60 to battery B^{15} . The magnet 60, upon energizing, attracts its armature and steps the ratchet wheel 61 one step in a 100 counter clockwise direction. As pointed out hereinbefore the cam wheels 63 and 64 do not move at this time, but the ratchet wheels 61 and 62, being rigid on the shaft, rotate, together with the shaft and store up tension 105 in the clock spring 222. After the impulses for this digit cease, the circuit of the relay 53 is broken at contacts 180 and 179 of the line relay and upon deenergizing allows the magnet 60 to deenergize in turn. The 110 ratchet wheels 61 and 62 are held in their operated position by means of the armature of the release relay 59 which engages the teeth of ratchet wheel 62.

Returning to the operation of selector D' 115 (Fig. 3): As soon as an idle trunk line in the level leading to the selector repeaters of this second exchange has been seized, the relay 76 is energized in the same manner as the relay 23 of selector D, and operates to 120 disconnect the operating relays of the selector from the trunk lines 203 and 204 and to connect said trunk lines through the wipers 102 and 103 to the selector repeater E'. A circuit is thereby closed for the line 125 relay 87 of the selector repeater E' extending from ground G^{16} through the lower winding of said relay springs 223 and 224, contact 107, wiper 103, springs 213 and 214.

and over the previously traced circuit through the bridge across the conductors 203 and 204 and back over the other side of the line through springs 208 and 209, 5 wiper 102, contact 105, springs 225 and 226, and upper winding of relay 87 to battery B²⁴. The line relay 87, upon energizing, closes a circuit for the relay 90, which in turn energizes and supplies a holding 10 ground for the relay 76 of the selector D', which extends from ground G¹⁸ through springs 230 and 231, relay 84, over the private conductor to contact 106, wiper 104, springs 211 and 212, and through the re- 15lays 76 and 80 to battery B²¹. A branch of the above traced circuit extends from the spring 212 through the relay 75 to battery B¹⁷. It will be seen that this circuit differs somewhat from the holding circuit of the 20 relay 23 of selector D in that the relay 75 is connected in multiple with the relays 76 and 80. All of the incoming selectors of each exchange which are accessible to incoming calls only are equipped with a relay 25 similar to the relay 75, the purpose of which is to so increase the current flowing in the circuit through the relay 84, or similar relays, as to allow said relays 84 to operatively energize to disconnect the register 30 controlling mechanism R' from the controlling relays of the selector repeater E'. The relay 84 will therefore energize over the above traced circuit and will maintain the circuit of the stepping magnet 232 of 35 the controlling mechanism open at the springs 234, and the circuit of the release magnet 233 open at the springs 235.

When the substation calling device is operated for the 5th digit, the circuit of the 40 line relay 45 of the selector repeater E is again interrupted a number of times. The separation of the springs 183 and 182 and the resulting interruption of the bridge across the conductors 203 and 204, in this 45 case opens the circuit of the line relay 87 of the selector repeater E' a corresponding number of times, to in turn control the vertical magnet 96 in the same manner as set forth in connection with the line relay 45 of 50 switch E. The slow acting relay 53 of the selector repeater E is again energized once in response to the operation of the line relay 45 over the previously traced circuit and again closes the circuit of the stepping magnet 60 of the register controlling mechanism R. The ratchet wheel 61 is thereupon given a second step and the relays 53 and magnet 60 again deenergize upon the cessation of the impulses through the line relay. 55 When the substation calling device is operated for the next digit, the circuit of the line relay 45 of the selector repeater E is again broken a number of times and again operates to repeat a corresponding number 60 of impulses to the line relay 87 of selector repeater E' (Fig. 3), and to step the ratchet wheel one more step through the medium of the relay 53. The line relay 87 in response to the impulses of this series, operates to control the circuit of the rotary magnet 97 70 to rotate the wipers 108—112 inclusive, onto the terminals of an idle trunk line in the desired subgroup, the trunk lines of which lead to a third exchange and which terminate in selector switches D² (Fig. 4). As soon as the wipers come to rest on the contacts 113—117 inclusive, a circuit is closed for the line relay 120 of the selector D² as follows: from ground G¹⁹ through the lower winding of the line relay 120, springs 246 80 and 245, contact 117, wiper 112, side switch wiper 101, resistance 247, lower winding of back bridge relay 86, springs 248 and 249, wiper 108, contact 113, springs 237 and 236, and upper winding of relay 120 to battery B³⁴. The back bridge relay 86 of the selector repeater E' being similar to the relay 46 of switch E does not operatively energize over this circuit and closes a circuit for the relay 250, which energizes to prepare the circuit of the vertical magnet. 90

When the substation calling device is operated for the next digit of the called number, the circuit of the line relay 45 is again opened a number of times and again operates to transmit a corresponding number of 100 impulses to the line relay 87 of selector repeater E' (Fig. 3). The side switch of the selector repeater E' being in third position at this time, each time the line relay 87 deenergizes the circuit of the line relay 120 of 105 the selector D² (Fig. 4) is broken at the springs 248 and 249 in the same manner in which the line relay 77 of selector D² was controlled by the line relay 45 of selector repeater E. It will thus be seen that the impulses for this and the following digits are relayed or repeated twice, first by the line relay 45, and again by the line relay 87. The line relay 120 operates in response to this digit, to raise the wipers 126, 127 and 110 128 to some level of the banks from which trunk lines lead to connectors similar to connector F. As soon as the impulses cease, the rotary magnet 125 is brought into operation in the usual manner to rotate the 115 wipers to the contacts of an idle trunk line, in this case the contacts 129, 130 and 131. Referring again to the selector repeater E, the relay 53 again energizes during the operation of relay 45 and closes the circuit of 120 stepping magnet 60, whereby the ratchet wheel 61 is given a fourth step. Although the slow-acting relay 85 of selector repeater E' is also energized at this time by the relay 87, the stepping magnet 232 is not en- 125 130

ergized, due to its circuit being held open at the springs 234 of relay 84 as previously explained.

As soon as the wipers 126, 127 and 128 come to rest on the contacts 129, 130 and 131, the relay 119 is energized and operates to extend the connection through the wipers 126 and 127 to the line relay 134 of connector F. The circuit for relay 134 extends from ground G²⁰ through the lower winding of relay 134, springs 251 and 252, contact 130, wiper 127, springs 244 and 245, and over the previously traced circuit through the lower winding of the back bridge relay 86 of selector repeater E' and springs 248 and 249, and back over the other side of the trunk through the springs 237 and 238, wiper 126, contact 129, springs 255 and 254, and upper winding of relay 134 to battery B³⁹. The relay 86 for reasons stated before does not energize over the circuit, the line relay 134, however energizes and closes a circuit from ground G²¹, springs 257 and 258 and relay 135 to battery B³⁹, the relay 135 in turn energizes and supplies a holding ground for the bridge cut-off relay 119 of the selector D². The circuit for the relay 119 extends from ground G²² through springs 261 and 262, springs 263 and 264, contact 131, wiper 128, springs 240 and 241, and through the relays 119 and 122 in multiple with the relay 118 to battery B³⁹.

When the substation calling device is operated for the next digit, the circuit of the line relay 45 of selector repeater E is again broken a number of times, and repeats the impulses to the line relay 87 of selector repeater E', which in this case, by the separation of the springs 248 and 249 repeats a corresponding number of impulses to the line relay 134 of the connector F over the previously traced circuit. The operation of the relay 53 of the selector repeater E again closes the circuit of stepping magnet 60, whereby the ratchet wheels 61 and 62 are given a fifth step. The relay 135 of connector F being slow-acting, the operation of the line relay 134 controls the circuit of the vertical magnet 142 to raise the wipers 146, 147, and 148 to the level of the bank in which the conductors of the desired line terminate, in the well known manner and as pointed out in the above mentioned Letters Patent #1,186,823. The slow-acting relay 137 which is included in the circuit of the vertical magnet, deenergizes, when the impulses for this digit cease, and substitute the rotary magnet 141 for the vertical magnet 142, to the control of the line relay 134 by means of the side switch.

When the substation calling device is operated for the last digit the circuit of the line relay 45 is again broken a number of times, the magnet 60 is also operated to give the ratchet wheels 61 and 62 a sixth and

last step, and the impulses are repeated over previously traced circuits to the line relay 134 of connector F. The line relay 134 operates in response to this series of impulses to deliver a corresponding number of impulses to the rotary magnet 141 whereby the wipers are rotated to the contacts of the desired line. Assuming the called line to be idle the side switch now passes to third position and the ringing relay 139 is intermittently operated to disconnect the calling line from the called line and to apply ringing current from the generator H to the terminals of the called line. The side switch wiper 265 on passing from second to third position establishes a guarding potential on the private contacts of the called line and closes an energizing circuit for the cut-off winding 145 of the called subscriber's individual switch C', whereby the line and operating magnets are disconnected from the line conductors.

When the called subscriber removes his receiver from the switch hook, in response to this signal, or as soon as the ringing relay 139 deenergizes, if it is energized at the time, a circuit is closed from ground G²³ through the relay 133, springs 266 and 267, springs 268 and 269, wiper 148, to and through the substation A' and back over the other side of the line through the wiper 146, springs 270 and 271, springs 272 and 273, and through the relay 132 to battery B³⁸. The relay 133, upon energizing, reverses the connections of the line relay 134 to the trunk conductors, and thereby reverses direction of the current flow in the trunk. The relay 132, upon energizing, closes a circuit from ground G²⁴ through the off-normal springs 274, springs 275, relay 276, and through the ring cut-off relay 138 to battery B⁴⁰. The relays 276 and 138 energize over this circuit, and the relay 138, upon energizing, opens the circuit of the ringing relay 139 and locks itself to ground G²⁴ by means of the springs 277. When the springs 277 engage it will be seen that the relay 276 is short circuited and immediately deenergizes. This momentary energization of relay 276 connects the battery B⁴⁴ in series with the release trunk. This battery has the negative pole grounded instead of the positive pole as the other battery and therefore a booster impulse is transmitted over the release trunk. This booster impulse is effective in local calls in one exchange and is used to operate a meter as explained in the before mentioned patent. Of course in the call which I have illustrated this booster impulse will be functionless as the release trunk does not extend to a meter. The reversal of current in the trunk by the relay 133 energizes the back bridge relay 86 of the selector repeater E' (Fig. 3), the current in both and 130

lower windings now assisting each other. The relay 86 upon energizing in turn reverses the battery to the trunk line 203 and 204 leading to the selector repeater E Fig. 2. This reversal of current causes the back bridge relay 46 of the selector repeater E to operatively energize, to reverse the battery in the trunk toward the calling line and to also close the contact of springs 184 and 185 whereby a circuit is closed for the release magnet 59 of the register controlling mechanism as follows: from ground G^{2a} through springs 184 and 185, springs 277 and 278, and magnet 59 to battery B^{11} . The magnet 59 upon energizing withdraws its armature from the teeth of the ratchet wheel 62 and allows the clock spring 222 to rotate the ratchet wheels 61 and 62 in a clock-wise direction to their normal position. The cam wheels 63 and 64 will now be rotated with the ratchet wheels by means of the dogs 70 and 70^a to close the springs 66 and 67 and 68 and 69 a number of times. The springs 66 and 67 will be operated twice the number of times that the magnet 60 was operated in the progress of the call, while the springs 68 and 69 will be operated the same number of times. The operation of the springs 66 and 67 at this time has no effect, the circuit therefrom being open at the contact 44^a in the bank. The operation of the springs 68 and 69 closes a circuit from booster battery B^{12} through resistance 280, wiper 39, contact 44, springs 68 and 69, springs 282 and 281, contact 34, wiper 32, springs 160 and 161, springs 19 and 15 and through the meter J to battery B. The battery B^{12} being connected in series with the battery B through the meter J, the meter will energize each time the springs 68 and 69 close. It will be seen therefore that the meter J will be operated a number of times corresponding to the number of digits which have been repeated over the trunk line to another exchange and in this case the subscriber's meter is operated six times or three times for each exchange through which the call has progressed.

After conversation is completed the connection is released by the restoration of the receiver at the calling station in a manner well known and which is fully described in the publications herein-referred to.

Let us suppose that a calling subscriber has called a party who fails to answer and the switches are released. As the registering mechanism R has been operated a number of steps during this call some means must be provided for preventing any false operation of the meter J under these circumstances. The slow-acting relay 51 has been added to the selector repeater E (Fig. 2) to overcome this difficulty. When the uncompleted connection is released, the release magnet 52 of the selector repeater E is ener-

gized and in turn closes a circuit for the relay 51 from ground G^{2a} through the springs 283 and 284 and relay 51 to battery B^{11} . The relay 51, upon energizing, closes a circuit for the release magnet 59 by means of the springs 285 and 286, and also opens the circuit which leads from the springs 66 and 69 to the release trunk. The register controlling mechanism will therefore be returned to normal position without sending any impulses of booster current to the subscriber's meter.

When a line is busy either by reason of having made a call or by reason of having been called, the busy relay 136 is energized in the usual manner and the calling subscriber is given a busy signal, whereupon the connection is released in the usual manner. Although I have shown a plurality of batteries throughout the drawings it will be understood that only one battery may be used for each exchange.

In Fig. 2 I have shown a set of contacts 41^a, 44^a and 45^a, which it is assumed lead to a fourth exchange (not shown) the trunk line to which is of double the length of the trunk line 203 and 204. When a call is made over this trunk some means must be provided to register double the number of times upon the subscriber's meter. When this line is called therefore the booster battery B^{12} instead of being connected to the spring 68 as in the prior case, is connected to the spring 67 by means of the local circuit from the contact 44^a. Now when this call has been set up and the called subscriber answers, the meter of the calling subscriber will be operated twice for each digit which was repeated to the outlying exchange, due to the cam wheel 63 having twice the number of teeth as the ratchet 61. It will readily be seen that the shaft of the controlling mechanism may carry any number of these cam wheels to carry out any ratio desired.

It will be seen therefore that I have provided a very efficient method of automatically registering long distance calls, and that the method of accomplishing this result is very flexible and may be varied in a number of ways by one skilled in the art to adapt it to any conditions. Although I have illustrated and explained my invention in connection with a particular type of automatic switches, it is of course understood that I do not wish to be limited to the exact construction shown and described, but my invention is capable of use with any other well known system.

What I claim as my invention is:—

1. In a telephone system, calling and called subscribers' lines, a registering device for each line, means for extending a connection from said calling line to a called line including a series of trunk lines of dif-

- ferent lengths, and means for automatically operating said registering device a predetermined number of times for each call in accordance with the length of the trunk lines used.
2. In a telephone system, calling and called subscribers' lines, a registering device for each line, means for extending said calling line into connection with a called line by means of a series of trunk lines of different lengths, and means controlled by the called subscriber for automatically operating said registering device a predetermined number of times for each call in accordance with the length of the trunk lines used.
3. In a telephone system, calling and called subscribers' lines, a registering device for each line, means for extending said calling line into connection with called lines by means of a plurality of trunk lines of different lengths, and means controlled by the called subscriber for operating said registering device a predetermined number of times for each call in accordance with the length of the trunk lines used.
4. In a telephone system, a plurality of exchanges, subscribers' lines in each exchange, means for extending a connection from a line in one exchange to a line in any other exchange, a register for the calling line, and means controlled by the called subscriber for operating said register a number of times, depending upon the number of exchanges through which said connection extends.
5. In a telephone system, a plurality of exchanges, subscribers' lines in each exchange, means for extending a connection from a line in one exchange to a line in any other exchange, a register for the calling line, and means controlled by the called subscriber for operating said register a predetermined number of times for each call, depending upon the distance between said connected exchanges.
6. In a telephone system, calling and called lines, a registering device for each line, means controlled solely by a calling subscriber for extending a connection from a calling to a called line by means of trunk lines of different lengths, and means controlled by the called subscriber for operating said registering device a predetermined number of times for each call depending upon the length of the trunk line used.
7. In a telephone system, calling and called lines, a registering device for each line, means controlled solely by a calling subscriber for extending a connection from a calling to a called line by means of trunk lines of different lengths, and automatic means controlled by the called subscriber for operating said registering device only a predetermined number of times depending upon the length of the trunk line used.
8. In a telephone system, a plurality of exchanges, subscribers' lines in each exchange, means controlled solely by the calling subscriber for extending a connection from a line in one exchange to a line in any other exchange, a register for the calling line, and means controlled by the called subscriber for operating said register a number of times, depending upon the number of exchanges through which said connection extends.
9. In a telephone system, calling and called subscribers' lines, a register for each line, means for extending a connection from a calling to a called subscriber's line by means of trunk lines of different lengths, a register controlling mechanism common to said lines, said mechanism controlled by the called subscriber to operate said register a predetermined number of times for each call, depending upon the length of trunk line used.
10. In a telephone system, a plurality of exchanges, subscribers' lines in each exchange, means for extending a connection from a line in one exchange to a line in any other exchange, a register for the calling line, a register controlling mechanism, said mechanism adapted to operate said register a variable number of times, depending upon the number of exchanges through which said call is extended.
11. In a telephone system, calling and called subscribers' lines, a register for each of said lines, means for extending a connection between said lines by means of trunk lines of different lengths, a register controlling mechanism, means for variably adjusting said mechanism, depending upon the length of trunk line used, and means for releasing said mechanism to operate said meter.
12. In a telephone system, calling and called subscribers' lines, a register for each of said lines, means for extending a connection between said lines by means of trunk lines of different lengths, a register controlling mechanism, means for variably adjusting said mechanism, depending upon the length of trunk line used, and means controlled by the called subscriber for releasing said mechanism to operate said meter.
13. In a telephone system, calling and called subscribers' lines, a register for each of said lines, means for extending a connection between said lines by means of trunk lines of different lengths, a register controlling mechanism, means for variably adjusting said mechanism, depending upon the length of trunk line used, and means for releasing said mechanism to operate said meter a variable number of times.
14. In a telephone system, calling and called subscribers' lines, a register for each of said lines, means for extending a connec-

tion between said lines by means of trunk lines of different lengths, a register controlling mechanism, means for variably adjusting said mechanism, depending upon the length of trunk line used, and means controlled by the called subscriber for releasing said mechanism to operate said meter a number of times.

15. In a telephone system, calling and 10 called subscribers' lines, a register for each of said lines, means controlled solely by the calling subscriber for extending a connection between said lines by means of trunk lines of different lengths, a register controlling mechanism, means for variably adjusting said mechanism, depending upon the length of trunk line used, and means for releasing said mechanism to operate said meter.

16. In a telephone system, a plurality of 20 exchanges, subscribers' lines in each exchange, means for extending a connection from a line in one exchange through any number of intervening exchanges to a called line in another exchange, a register for the calling line, a register controlling mechanism, means for variably adjusting said mechanism depending upon the number of exchanges through which said connection extends, and means for releasing said mechanism to operate said register.

17. In a telephone system, a plurality of exchanges, subscribers' lines in each exchange, means for extending a connection from a line in one exchange through any 35 number of intervening exchanges to a called line in another exchange, a register for the calling line, a step-by-step register controlling mechanism, means for variably adjusting said mechanism depending upon the number of exchanges through which said connection extends, and means for releasing said mechanism to operate said register.

18. In a telephone system, a plurality of exchanges, subscribers' lines in each exchange, means for extending a connection from a line in one exchange through any 45 number of intervening exchanges to a called line in another exchange, a register for the calling line, a step-by-step register controlling mechanism, means for operating said mechanism a number of steps depending upon the number of exchanges through which said connection extends, and means for releasing said mechanism to operate said register.

19. In a telephone system, a line, a register for said line, a circuit for said register, a step-by-step register controlling mechanism associated with said register, a circuit 50 closer controlled by said mechanism, means for operating said mechanism a predetermined number of times for each call, and means for automatically releasing said mechanism to operate said register a pre- 65 determined number of times each time the

mechanism is brought into use to assess different tolls, by closing said circuit a number of times through said circuit closer.

20. In a telephone system, calling and 70 called subscribers' lines, switches for connecting any two of said lines, means for controlling said switches by a plurality of series of impulses to establish such connection, a register for the calling line, and means for operating said register a number 75 of times, depending upon the number of series of impulses used.

21. In a telephone system, calling and 80 called subscribers' lines, a register associated with each line, means for extending a connection between two of said lines comprising a plurality of automatic switches, a register controlling mechanism associated with one of said switches, means for sending a plurality of series of impulses to said 85 switches from the calling line to extend said connection, means for operating said mechanism once for each series of impulses, and means for thereafter releasing said mechanism to operate said register.

90 22. In a telephone system, calling and called subscribers' lines, a register associated with each line, means for extending a connection between two of said lines comprising a plurality of automatic switches, a register controlling mechanism associated with one of said switches, means for sending a plurality of series of impulses to said 95 switches from the calling line to extend said connection, means for operating said mechanism once for each series of impulses, and means controlled by the called subscriber for thereafter releasing said mechanism to operate said register.

100 23. In a telephone system, calling and 105 called subscribers' lines, a register associated with each line, means for extending a connection between two of said lines comprising a plurality of automatic switches, a register controlling mechanism associated with one of said switches, means for sending a plurality of series of impulses to said 110 switches from the calling line to extend said connection, means for operating said mechanism once for each series of impulses, and means for thereafter releasing said mechanism to operate said register a number of times, depending upon the number of times said mechanism was operated.

115 24. In a telephone system, calling and 120 called subscribers' lines, a register associated with each line, means for extending a connection between two of said lines comprising a plurality of automatic switches, a register controlling mechanism associated with one of said switches, means for sending a 125 plurality of series of impulses to said switches from the calling line to extend said connection, means for operating said mechanism once for each series of impulses, and 130

- means for thereafter releasing said mechanism to operate said register a number of times, depending upon the number of series of impulses sent out by said calling subscriber.
25. In a trunking system, a repeater, a register controlling mechanism associated with said repeater, incoming selectors and local selectors having access to said repeater, means for operating said controlling mechanism when the repeater is seized by a local selector and means for rendering said mechanism inoperative when the repeater is seized by an incoming selector.
- 15 26. In a telephone system, a calling line, a meter for said line, an automatic switch accessible to said line, a meter controlling mechanism associated with said switch, a plurality of called lines accessible to said switch, means for extending a connection from the calling line to said automatic switch, means for then operating said switch to seize any one of said called lines, and means for operating said mechanism a predetermined number of times before certain of said called lines are connected with and means for operating said mechanism a different number of times before others of said lines are connected with, and a circuit for said meter controlled by said mechanism.
- 25 27. In a telephone system, calling and called lines, means for connecting any two of said lines including trunk lines of different lengths, a register for each line, a register controlling mechanism common to said lines, an operating magnet for said mechanism and a release magnet for said mechanism, means for operating said operating magnet a number of times when a trunk line of one length is used and a greater number of times when a longer trunk line is used, and means for operating said release magnet to release said mechanism to thereby operate said register.
- 40 28. In a telephone system, subscribers' lines, a register for each of said lines, means for extending local and long distance connections from one of said lines, and means controlled by the called subscriber for operating said register only once to register each local call and a plurality of times to register each long distance call.
- 45 29. In a telephone system, subscribers' lines, a register for each line, means for extending local and long distance connections from one of said lines, a register controlling device for controlling said register, said device controlled by the called subscriber for operating said register to register a long distance connection only.
- 55 30. In a telephone system, subscribers' lines, a register for each of said lines, means controlled solely by the calling subscriber for extending local and long distance connections from one of said lines, and means controlled by the called subscriber for operating said register only once to register each local call and a number of times to register each long distance call.
- 65 31. In a telephone system, a meter, a meter controlling mechanism for controlling said meter, a trunking switch associated with said mechanism for controlling the operation thereof, trunk lines accessible to said switch, means for operating said switch to seize any one of said lines, and discriminating means associated with each trunk line whereby said mechanism is operated only once before one trunk line is seized and a number of times before another trunk line is seized in both cases through the medium of said controlling mechanism.
- 70 32. In a telephone system, a meter, a meter controlling mechanism for controlling said meter, a trunking switch associated with said mechanism for controlling the operation thereof, trunk lines accessible to said switch, means for operating said switch to seize any one of said lines, and means whereby said meter is operated in one manner when one trunk line is seized and in another manner when another trunk line is seized in both cases through the medium of said controlling mechanism in accordance with all the digits of a called number.
- 75 33. In a telephone system, a meter, a connector switch operated in accordance with the digits of a called number to find a called line, said meter controlled over the called line through the medium of said connector switch in accordance with all the digits of the called number.
- 80 34. In a telephone system, a meter, a connector switch for seizing a called line, a trunking switch for seizing said connector, means associated with said trunking switch and controlled thereby for controlling said meter, said means also controlled from the called line through the medium of said connector switch to operate said meter in accordance with all the digits of the called number.
- 85 35. In a telephone system, a meter, means for operating said meter in accordance with all the digits of a called number a trunk switch associated with said means, trunk lines of different lengths accessible to said switch, and means whereby said meter is operated in one manner when a trunk line of one length is seized by said switch and in another manner when a trunk line of another length is seized.
- 90 36. In a telephone system, a calling line, a meter for said line, switches for establishing connections from said line, means associated with one of said switches for operating the meter, said means operated once for each digit of a called number used in operating said switches and controlled

after a connection is set up to operate said meter as many times as said means was operated during the establishment of the call.

- 5 37. In a telephone system, calling lines, a meter for each line, a device common to said lines for operating said meters, means for extending a connection from one of said lines and associating said device therewith, 70
 10 means for operating said device a variable number of times during the extension of a connection, and means for controlling said device after the call is extended to operate the meter as many times as the device was operated during the extension of the call.

38. In a telephone system, a calling line, a meter for said line, a step by step register controller for controlling said meter, 20
 20 means controlled by the digits of a called number to extend a call to called lines, and to operate said register controller a definite number of times depending upon the number of digits in a called number, and means 25 controlled by the response of the called subscriber for causing said register controller to operate said meter once for each digit of the called number.

39. In a telephone system, a meter, a 30
 30 meter controlling device, means controlled by each digit of a called number when establishing a connection for storing up energy in said device, and means controlled after the establishment of a connection for 35 allowing said device to deliver the energy stored therein to the meter to operate the same.

40. In a telephone system, a meter controlling device, means for establishing a 40
 40 connection between two subscribers' lines in accordance with the digits of a called number, said device controlled by each digit of a called number to store up an impulse of current and controlled after the connection 45 is established to deliver the stored up impulses to said meter to operate the same.

41. In a telephone system, a calling line, a meter for said line, a step by step register controller for controlling said meter, 50
 50 means controlled by the digits of a called number to extend a call to called lines, and to operate said register controller a definite number of times depending upon the number of digits in a called number, and means 55 controlled by the response of the called subscriber for causing said register controller to operate said meter once for each digit of the called number.

42. In a telephone system, a meter, a 60
 60 meter controlling device, means controlled by each digit of a called number when establishing a connection for storing up energy in said device, and means controlled after the establishment of a connection for 65 allowing said device to deliver the energy

stored therein to the meter to operate the same.

43. In a telephone system, a meter, a meter controlling device, means for establishing a connection between two subscribers' lines in accordance with the digits of a called number, said device controlled by each digit of a called number to store up an impulse of current controlled after the connection is established to deliver the 75 stored up impulses to said meter to operate the same.

44. In a telephone system, a calling line, a meter for said line, switches for establishing connections from said line, means associated with one of said switches for operating the meter, said means operated once for each digit of a called number used in operating said switches and controlled after a connection is set up to operate said meter 85 as many times as said means was operated during the establishment of the call.

45. In a telephone system, calling lines, a meter for each line, a device common to said lines for operating said meters, means 90 for extending a connection from one of said lines and associating said device therewith, means for operating said device a variable number of times during the extension of a connection and means for controlling said 95 device after the call is extended to operate the meter as many times as the device was operated during the extension of the call.

46. In a telephone system, a calling and a called line, automatic switches, means 100 controlled by the subscriber on the calling line for operating said switches successively to extend a connection from the said calling line over a plurality of link conductors to the called line, a meter for the calling line, a meter controlling device operated one or more times as each link conductor is added to the connection, said device controlled after the completion of the connection to operate said meter in accordance 110 with the number of times the device was operated during the extension of the connection.

47. In a telephone system, a calling line, a called line, an automatic switch accessible 115 to said calling line and controllable therefrom to extend connections to the called line, a meter for the calling line, a meter controlling device associated with the switch for operating said meter, means for operating said device a plurality of times during 120 the extension of the call, the number of times the device is operated depending upon the number of digits delivered by the calling subscriber, said device then controlled 125 to operate the meter.

48. In a telephone system, a line, a meter therefor, an automatic switch accessible to said line, a meter controlling device individual to said switch, a trunk circuit ac- 130

essible to said switch for use by the calling subscriber for extending connections from said line to called lines requiring varying toll charges, said device adjusted during the extension of the call over said trunk line in accordance with the proper charge and controlled by the response of the called

subscriber to operate said meter in accordance with the adjustment.

Signed by me at Chicago, Cook county, 10 State of Illinois, this 26th day of April, 1917.

WILLIAM WALTER OWEN.
